ELECTRIC GRIDDLE

David L. Painter, Evanston, Ill., assignor to West Bend
Aluminum Co., West Bend, Wis., a corporation of
Wisconsin

Application March 17, 1958, Serial No. 50,066

Term of patent 14 years

(Cl. D81—10)

Fig. 1 is a top plan view of an electric griddle showing my design;

Fig. 2 is a view in front elevation;

Fig. 3 is a view in left side elevation;

Fig. 4 is a sectional view taken on the line 4-4 of Fig. 1; and

Fig. 5 is an enlarged fragmentary view of a portion of the top of the control plug element illustrating the design detail of said element and of the handles.

I claim:

The ornamental design for an electric griddle, substantially as shown.
